(57) **CLAIM**

We claim the ornamental design for a demolition tool, as shown and described.

DESCRIPTION

FIG. 1 is a front perspective view of an embodiment of the claimed design;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.

The broken lines depict portions of the demolition tool in which the design is embodied that are not considered part of the claimed design.

1 Claim, 4 Drawing Sheets(56)
